AEROSOL DILATING MEDICAL COMPOSITION

Lucien Dautrebande, Brussels, Belgium, assignor to Aerosol Corporation of America, New York, N. Y., a corporation of Delaware

No Drawing. Application October 25, 1951,
Serial No. 253,225

10 Claims. (Cl. 167—58)

1

This invention relates to aerosol medication and more particularly to therapeutic solutions suitable for inhalation as aerosols in the treatment of asthma and related disorders.

For the successful treatment of bronchial asthma, status asthmaticus and other diseases characterized by spastic bronchoconstriction, it is necessary to employ drugs which exercise a pneumodilating action. In the use of such drugs, a problem has existed with respect to bringing the therapeutic agents into contact with the constricted bronchial mucosa in order to produce pneumodilatation. It has been found that the administration of sympathomimetic drugs by means of aerosols, i. e., dispersions in air of solutions of the drugs, in which the individual particles present are of the order of one micron or less in size, makes possible the penetration of the lungs by these therapeutic agents so that their beneficial therapeutic effects may be exerted directly upon the bronchial mucosa. Thus, it has been possible to bring about effective pneumodilatation by means of sympathomimetic drugs without employing parenteral administration.

Heretofore 1(3',4' - dihydroxyphenyl) - 2-isopropylaminoethanol, commonly known as "Aludrine," has been found to be an exceedingly efficient drug for the treatment of asthma, and solutions of Aludrine have been administered therapeutically as aerosols by inhalation for purposes of treatment of asthmatic conditions and the like. It has been found, however, that where solutions of Aludrine are employed in sufficient concentration to bring about a full pneumodilatation, as is generally desirable, it is practically impossible to avoid the occurrence of unpleasant side effects. Other substances, such as epinephrine, ephedrine, atropine, amphetamine, and the like, although somewhat less effective, have also been used in the treatment of asthma. However, because of the appearance of side effects or actual toxic manifestations during or after the period of treatment, the therapeutic application of sympathomimetic drugs in diseases characterized by the occurrence of spastic bronchoconstriction has had to be carefully regulated. It has generally been necessary to provide rigid schedules of administration for the aforementioned drugs to prevent their too frequent use, in order to minimize the occurrence of the undesirable and even dangerous side effects.

It is an object of this invention to provide a solution for therapeutic administration by inhalation as an aerosol, which exercises a power-

ful pneumodilating effect without danger of side effects or toxic manifestations through long-continued therapeutic use. It is a further object of this invention to provide therapeutic solutions which when inhaled in the form of an aerosol are capable of exerting a maximum pneumodilating effect. A further object of this invention is the provision of therapeutic solutions for use as aerosols in which the ingredients are individually present in quantities proportionately much smaller than has heretofore been deemed possible to produce the above-mentioned maximum effect. Other objects of the invention will be apparent from the disclosures made hereinafter.

In accordance with the above and other objects of this invention I have discovered that solutions containing procaine or a salt thereof and one or more bronchodilating agents selected from the group consisting of 1-(3',4'-dihydroxyphenyl) - 2 - isopropylaminoethanol (Aludrine), and cyclopentylmethylaminopropane (cyclopentamine), and/or salts of said agents have especially valuable properties for inhalation treatment of asthma and other diseases in which pneumodilatation is of therapeutic benefit. The new compositions of my invention contain procaine and pneumodilating drugs in smaller amounts than would be expected for full therapeutic effect, because of synergistic action between the procaine and the sympathomimetic ingredients whereby their pneumodilating action is markedly potentiated. When administered as aerosols, the new compositions afford dramatic relief in cases of asthmatic crisis. Moreover, no appreciable side effects and no toxic symptoms are evidenced even though administration of the solutions as aerosols is relatively long-continued or often repeated.

The vehicle or diluent employed in the new compositions can be any of the pharmaceutical diluents already known to the art not to be harmful to the lung tissues when inhaled as an aerosol. Examples of suitable diluents include water, isotonic salt solution, the lower glycols such as triethylene glycol and propylene glycol, especially aqueous solutions of these glycols, and the like.

Procaine and the other bronchodilating agents contained in the novel compositions are organic bases and are generally used in the form of their pharmaceutically useful water soluble acid addition salts where the composition contains an aqueous vehicle. By the term "pharmaceutically useful" it is intended to designate those salts which do not substantially increase the toxicity

2

of the base, and which are compatible with the vehicle employed. Examples of such salts are the hydrochloride, sulfate, nitrate, phosphate, hydrobromide, acetate and like salts of the procaine and the sympathomimetic bases. However, it will be obvious to those skilled in the art that vehicles in which the organic bases are soluble (e. g. the lower glycols) can be used and that with such vehicles the active substances can be employed in the form of their bases.

Procaine is employed in the new compositions in concentration of from about 0.1 to about 1.5 percent and the sympathomimetic agents are present in concentration of from about 0.1 to about 1.0 percent. Desirably from about 0.2 to about 0.5 percent of procaine and from about 0.2 to about 0.5 percent of each sympathomimetic drug which is employed are present.

An example of simple solutions intended for use as aerosols and embodying compounds which produce the novel effects of my invention is as follows:

EXAMPLE 1

Procaine hydrochloride-----g-- 1
1(3',4'-dihydroxyphenyl)-2-isopropylamino-
ethanol hydrochloride-----g-- 0.5
Water to make 100 cc.
Acid addition salts of cyclopentylmethylamino-
propane can be used together with or in place
of the Aludrine.

For therapeutic use, the above solution is placed in any of the commercially available devices known as "aerosolizers" or "nebulizers" and from two to ten or more inhalations are made of the aerosol which is produced therefrom. A lasting pneumodilatation takes place, with relief from asthmatic symptoms. The treatment is repeated as indicated.

The synergistic effect obtainable in this composition is demonstrated by the following:

Table

Example No.	Aerosol of--	Volume of Aerosol inhaled (in liters)	Dilation Range (Maximum Increase in actual Lung Volume in cc.)	Duration of Dilation (in minutes)
A-----	1% aqueous solution of procaine hydrochloride.	12	150 to 250-----	2 to 3.
B-----	0.5% aqueous solution of 1(3',4'-dihydroxyphenyl)-2-isopropylaminoethanol hydrochloride.	12	300 to 500-----	4 to 6.
1-----	Aqueous solution containing 1% procaine hydrochloride and 0.5% of 1(3',4'-dihydroxyphenyl)-2-isopropylaminoethanol hydrochloride.	12	1,000 to 1,200-----	10 to 15.

Provided that the mean micellary size of the aerosol is equal to or below 0.5 micron, the synergistic effect of the procaine aleudrine composition is regularly apparent as in Example 1. Considering the increase in the extent of the pneumodilatation and of its duration, the results obtained with this pneumodilating composition cannot, therefore, be due to a simple additive effect.

An example of a composition which has a powerful pneumodilating effect and which is especially efficient in cases of asthma is the following:

EXAMPLE 2

Procaine hydrochloride-----G. 0.2
1(3',4'-dihydroxyphenyl)-2-isopropylaminoethanol hydrochloride----- 0.25
Atropine sulfate----- 0.1

4
Cyclopentylmethylaminopropane hydro-
chloride ----- 0.5
Propylene glycol----- 80
Water to make 100 g.

5 The solution is placed in an aerosolizer and several inhalations are made of the aerosol which is produced. The treatment can be repeated at hourly intervals, or more frequently as required to provide relief.
10 Other materials can, if desired, be included in the compositions of this invention in order to obtain special therapeutic or other effects not achieved by the presence of only the combination of the procaine and sympathomimetic amine.
15 Thus, for example, anti-secretive drugs such as atropine, antiseptics for the respiratory system such as creosote, guaiacol, menthol, eucalyptol and the like, isotonicity-producing substances such as sodium chloride and the like, additional vehicles such as propylene glycol, triethylene glycol and the like, chemotherapeutic agents such as the sulfonamides, and antibiotics including penicillin, streptomycin, Aureomycin, Chloramphenicol, bacitracine, tyrotricaine, and the like can be employed if desired in conjunction with the fundamental ingredients of the compositions of the invention as shown in Example 1. The following examples illustrate compositions providing effective pneumodilatation, thus permitting a better penetration of the lung tissues by the chemotherapeutic or antibiotic drug contained therein. Such preparations are especially useful in bacterial infections of the respiratory tract.

EXAMPLE 3

Procaine hydrochloride----- 0.3 g.
1(3',4'-dihydroxyphenyl)-2-isopropylaminoethanol sulfate----- 0.25 g.
Sodium Penicillin-G----- 1 million units.
40 Water to make 100 cc.

60 Ten to twenty inhalations of a fine aerosol or more of the above composition produces a substantial pneumodilatation and concomitantly provides a more uniform and penetrating pulmonary penicillin therapy.

EXAMPLE 4

65 Procaine hydrochloride-----G. 0.2
Cyclopentylmethylaminopropane hydrochloride----- 0.5
1(3',4'-dihydroxyphenyl)-2-isopropylamino-
70 ethanol hydrochloride----- 0.25
Streptomycin hydrochloride----- 5.0
Water to make 100 cc.

The solution is placed in an aerosolizer and from ten to twenty inhalations or more are made at each treatment. The entry of the streptomycin-

cin into the lung passages is facilitated by the pneumodilatation which takes place.

I claim:

1. A composition adapted for inhalation as a therapeutic aerosol, comprising a solution of procaine hydrochloride, 1(3',4'-dihydroxyphenyl)-2-isopropylaminoethanol hydrochloride, and cyclopentylmethylaminopropane hydrochloride in a vehicle which is without harmful effect on lung tissue.

2. A composition adapted to inhalation as a therapeutic aerosol, comprising about 0.2 percent procaine hydrochloride, about 0.25 percent 1(3',4'-dihydroxyphenyl)-2-isopropylaminoethanol hydrochloride, and about 0.5 percent cyclopentylmethylaminopropane hydrochloride dissolved in a pharmaceutical diluent.

3. A composition adapted for inhalation as a therapeutic aerosol, comprising a solution in a pharmaceutical diluent of a member of the group consisting of procaine and pharmaceutically useful acid addition salts thereof, together with at least one member of the group consisting of 1(3',4'-dihydroxyphenyl)-2-isopropylaminoethanol and cyclopentylmethylaminopropane, and pharmaceutically useful acid addition salts thereof.

4. A pneumodilating aerosol composition comprising a solution in a pharmaceutical diluent of from about 0.1 to 1.5 percent of a member of the group consisting of procaine and pharmaceutically useful acid addition salts thereof, and from about 0.1 to 1.0 percent of a member of the group consisting of 1(3',4'-dihydroxyphenyl)-2-isopropylaminoethanol, and cyclopentylmethylaminopropane and pharmaceutically useful acid addition salts thereof.

5. A pneumodilating aerosol composition comprising from about 0.2 to about 0.5 percent of a member of the group consisting of procaine and pharmaceutically useful acid addition salts thereof, and from about 0.2 to about 0.5 percent of at least one member of the group consisting of 1(3',4'-dihydroxyphenyl)-2-isopropylaminoethanol and cyclopentylmethylaminopropane, and pharmaceutically useful acid addition salts thereof.

6. A pneumodilating aerosol composition comprising a pharmaceutical diluent and dissolvent

therein in a total concentration less than about 2.5 percent, a mixture of procaine hydrochloride and 1(3',4'-dihydroxyphenyl)-2-isopropylaminoethanol hydrochloride.

5 7. A pneumodilating aerosol composition comprising a solution in a pharmaceutical diluent of about 0.2 percent of procaine hydrochloride and about 0.25 percent of 1(3',4'-dihydroxyphenyl)-2-isopropylaminoethanol hydrochloride.

10 8. A composition adapted for inhalation as a therapeutic aerosol, comprising a solution of procaine hydrochloride, 1(3',4'-dihydroxyphenyl)-2-isopropylaminoethanol hydrochloride, cyclopentylmethylaminopropane hydrochloride in a vehicle which is without harmful effect on lung tissue and an antibiotic.

9. A composition adapted for inhalation as a therapeutic aerosol, comprising a solution of procaine hydrochloride, 1(3',4'-dihydroxyphenyl)-2-isopropylaminoethanol hydrochloride, cyclopentylmethylaminopropane hydrochloride in a vehicle which is without harmful effect on lung tissue and penicillin.

10 10. A composition adapted for inhalation as a therapeutic aerosol, comprising a solution of procaine hydrochloride, 1(3',4'-dihydroxyphenyl)-2-isopropylaminoethanol hydrochloride, cyclopentylmethylaminopropane hydrochloride in a vehicle which is without harmful effect on lung tissue and streptomycin.
